UNITED STATES PATENT OFFICE.

SAMUEL A. DUGAN, OF GALVESTON, TEXAS.

INCINERATOR.

Application filed February 19, 1924. Serial No. 693,861.

To all whom it may concern:

Be it known that I, SAMUEL A. DUGAN, a citizen of the United States, residing at Galveston, in the county of Galveston and 5 State of Texas, have invented certain new and useful Improvements in Incinerators, of which the following is a full, clear, and exact specification.

This invention relates to incinerators especially designed for use in homes for burning trash, garbage and slops in order to prevent breeding of flies and mosquitoes, to starve rats, mice and bugs, and to prevent the accidental starting of destructive fires in 10 or about the homes. These incinerators may be made in different sizes adapting them for use in school yards, public parks, public automobile camps, railroad stations, hotels and restaurants, in fact, anywhere that rubbish 15 and trash accumulates, even on public drives where the incinerators may be placed at intervals and trash hauled to each one for burning, the ashes being utilized for fertilizing flower beds on highways or in parks.

It is the object of the present invention 20 to provide an incinerator of simplified and improved construction which is inexpensive to manufacture and which may be used effectively for burning slops and garbage as 25 well as trash, so that said slops and garbage cannot be eaten by rats, roaches, flies, or other vermin. A special object is to construct the incinerator in such a way that the 30 burning of the trash will aid in burning the garbage and slops. Another special object 35 is to arrange the parts of the incinerator so that it may be utilized for burning trash alone if desired. Other objects will appear 40 as the description proceeds.

The invention will be first hereinafter 45 described in connection with the accompanying drawings, which constitute part of this specification, and then more specifically defined in the claims at the end of the description.

In the accompanying drawings, wherein 50 similar reference characters are used to designate corresponding parts throughout the several views:

Figure 1 is a front elevation of an incinerator constructed substantially in accordance with this invention.

Figure 2 is a vertical section taken on line II-II of Figure 1.

Figure 3 is a horizontal section on the line III-III of Figure 2.

Figure 4 is a plan view of the incinerator with the hook for supporting the cover swung upward to horizontal position.

Figure 5 is a section on the line V-V of 60 Figure 2.

Figure 6 is a vertical section of the upper portion of the incinerator taken on the line VI-VI of Figure 4 and showing the cover raised and supported by the hook, and 65

Figure 7 is a section on the line VII-VII of Figure 2 and showing the draft door raised.

The body 1 of the incinerator is preferably made of sheet iron in vertical cylindrical form, and is supported above the ground by a plurality of legs 2, three of which are shown in the drawings spaced equidistantly about said body and formed of angle iron extending upward along said body to which they are riveted at 3 and which they serve to reinforce. An ash-dump opening 4 is formed in the bottom 5 of the body 1, and said opening is normally closed by a slide 6 mounted on the inner edges of double edged runners 7 at the sides of the opening and below the bottom 5. In line with the outer end of the slide 6, a draft opening 8 is formed in the side of said body 1, and a vertically movable door 9 is fitted over said draft opening, being guided at its edges in grooves 10, see Figure 3. Said closure 9 has a handle portion 11 projecting outwardly at its upper end, and a vertical series of perforations 12 are formed in said door in line with a perforation 13 in the wall of the body 1 above the opening 8, whereby the door 9 may be supported at different levels by inserting a pin 14 through said perforation 13 and any one 80 of the perforations 12 in order to regulate 85 the draft.

An ash pan 15 is mounted below the ash-dump opening 4 and preferably supported on the outer edges of the runners 7 by angle irons 70 suitably secured along the lateral edges of said pan which is used for catching the ashes when the incinerator is used in the house. When the incinerator is used outdoors, the ash pan may be omitted and the ashes dumped on the ground through the opening 4 by drawing out the slide 6.

A feed chute 16 for trash is arranged at the front of the incinerator, being secured to the lower portion of the body 1, as best shown in Figures 1 and 2. Said chute 16 is provided with a removable cover 17 having a

handle 18, said cover conforming at its inner end to the curvature of the body 1 and having a downwardly turned flange 19 at its sides and outer end to fit over the upper edge 5 of said chute.

A cover 20 is hinged at 21 to the body 1, and at a diametrically opposite point on said cover there is secured a metal strip 22 projecting a short distance beyond the edge of 10 the cover and having a hook 23 pivotally connected to its projecting end portion, as best shown in Figures 1, 4 and 6. When the cover 20 is swung upward on the hinge 21, as shown in Figure 6, the hook 23 is engaged 15 with a perforation 24 in the upper portion of the angle iron of the adjacent leg 2 for supporting said cover in its raised position. The cover 20 has a central opening 25 in which a smoke stack 26 is fitted and secured 20 by external angle brackets 27 and an internal flange 28 on the lower end of said stack. The upper end of the stack 26 is fitted with a cap 29 of wire mesh material to arrest 25 sparks without interfering with the draft.

Within the body 1 of the incinerator and 25 removably supported on angle brackets 30 preferably arranged slightly above the level of the top of the trash chute 16, a perforated plate 31 is placed for holding wet garbage and slops to be burned by the fire from the trash introduced into the bottom portion of said body through said chute 16. Said perforated slop plate 31 has a central opening 32 in which is removably mounted a 30 short supplemental stack 33, which is of less diameter than the main stack 26 and which extends concentrically into the lower end of said main stack, see Figure 2. Said supplemental stack 33 has angle brackets 34 riveted thereto and spaced slightly above its lower end for supporting the same on the slop plate 31 with the lower end portion of said short stack extending down through the central opening 32 in said plate. It will be 35 noted that the upper end portion of the short stack 33 is spaced inward from the walls of the lower end portion of the main stack 26 so that the main draft up through the short stack to the main stack will induce a secondary draft up through the perforation in the plate 31 and around the upper portion of the short stack which extends into the lower end portion of said upper stack. This induced or secondary draft serves to burn 40 or incinerate the wet garbage and slops which are placed on the perforated plate 31, while the direct draft up through the short stack 33 to the main stack 26 supports the combustion of the trash in the bottom 45 portion of the incinerator so that the burning thereof will not be stopped by the moisture in the wet garbage or slops, and the fire from said burning trash may consequently be utilized for effectively incinerating said 50 wet garbage and slops.

When the cover 20 of the incinerator is swung open, as illustrated in Figure 6, and already described herein, wet garbage and slops may be readily placed on the perforated plate 31 around the short stack 33. In 70 case only trash is to be burned, the perforated plate 31 and short stack 33 may be taken out through the open upper end of the incinerator, and the latter may be then filled with trash from the top as well as 75 through the chute 16, the draft then being directly up through the main stack 26.

Referring again to the draft door 9, it will be noted that it is illustrated in raised position in Figure 7. It will also be noted in 80 Figure 1 that the pin 14 when not in use may be hung by a wire 34 from the hand portion 11 of said draft door 9.

The supplemental or short stack 33 is made removable in order to permit the 85 burned slops to be raked through the central opening 32 in the slop plate 31 down into the lower part of the incinerator.

I claim:

1. An incinerator of the character described having a main stack rising from its top, a perforated plate for supporting wet garbage and slops in the upper portion of said incinerator, an opening in said perforated plate in line with said main stack, 90 and a supplemental stack extending upwardly from said opening in said perforated plate, there being a space in the bottom portion of the incinerator below said plate for burning trash, whereby the fire from said trash is utilized for incinerating the wet garbage and slops on said perforated plate.

2. An incinerator of the character described having a main stack rising from its top, a perforated plate for supporting wet garbage and slops in the upper portion of said incinerator, an opening in said perforated plate in line with said main stack, and a supplemental stack extending upwardly from said opening in said perforated plate, the upper end portion of said supplemental stack extending into and being spaced inwardly from the lower end portion of the main stack, there being a space in the bottom portion of the incinerator below said plate for burning trash, whereby the fire from said trash is utilized for incinerating the wet garbage and slops on said perforated plate.

3. An incinerator of the character described having a main stack rising from its top, a perforated plate for supporting wet garbage and slops in the upper portion of said incinerator, an opening in said perforated plate in line with said main stack, and a supplemental stack extending upwardly from said opening in said perforated plate, there being a space in the bottom portion of the incinerator below said plate for

burning trash, whereby the fire from said trash is utilized for incinerating the wet garbage and slops on said perforated plate, said perforated plate and supplemental stack being removable from the incinerator when the latter is to be used for burning trash alone.

4. An incinerator of the character described having a main stack rising from its top, a perforated plate for supporting wet garbage and slops in the upper portion of said incinerator, an opening in said perforated plate in line with said main stack, and a supplemental stack extending upwardly from said opening in said perforated plate, there being a space in the bottom portion of the incinerator below said plate for burning trash, whereby the fire from said trash is utilized for incinerating the wet garbage and slops on said perforated plate, said main and supplemental stacks being arranged concentrically of each other and in the center of the top of the incinerator and in the center of said perforated plate, respectively.

5. An incinerator of the character described having a main stack rising from its top, a perforated plate for supporting wet garbage and slops in the upper portion of said incinerator, an opening in said perforated plate in line with said main stack, and a supplemental stack extending upwardly from said opening in said perforated plate, there being a space in the bottom portion of the incinerator below said plate for burning trash, whereby the fire from said trash is utilized for incinerating the wet garbage and slops on said perforated plate, the top of the incinerator being hinged to swing upward for permitting the wet garbage and slops to be placed on the perforated plate around the supplemental stack.

6. An incinerator of the character described having a main stack rising from its top, a perforated plate for supporting wet garbage and slops in the upper portion of said incinerator, an opening in said perforated plate in line with said main stack, and a supplemental stack extending upwardly from said opening in said perforated plate, there being a space in the bottom portion of the incinerator below said plate for burning trash, whereby the fire from said trash is utilized for incinerating the wet garbage and slops on said perforated plate, the top of the incinerator being hinged to swing upward for permitting the wet garbage and slops to be placed on the perforated plate around the supplemental stack, and means for supporting said hinged top in raised position.

7. An incinerator of the character described having a main stack rising from its top, a perforated plate for supporting wet garbage and slops in the upper portion of said incinerator, an opening in said perforated plate in line with said main stack, and a supplemental stack extending upwardly from said opening in said perforated plate, there being a space in the bottom portion of the incinerator below said plate, for burning trash, whereby the fire from said trash is utilized for incinerating the wet garbage and slops on said perforated plate, the top of the incinerator being hinged to swing upward for permitting the wet garbage and slops to be placed on the perforated plate around the supplemental stack, and means for supporting said hinged top in raised position, said means comprising a hook attached to the free edge portion of said top and adapted to interlock with the top portion of the incinerator.

8. An incinerator of the character described having a main stack rising from its top, a perforated plate for supporting wet garbage and slops in the upper portion of said incinerator, an opening in said perforated plate in line with said main stack, and a supplemental stack extending upwardly from said opening in said perforated plate, there being a space in the bottom portion of the incinerator below said plate for burning trash, whereby the fire from said trash is utilized for incinerating the wet garbage and slops on said perforated plate, and a trash chute communicating with the interior of the incinerator below the level of said perforated plate.

9. An incinerator of the character described having a main stack rising from its top, a perforated plate for supporting wet garbage and slops in the upper portion of said incinerator, an opening in said perforated plate in line with said main stack, and a supplemental stack extending upwardly from said opening in said perforated plate, there being a space in the bottom portion of the incinerator below said plate for burning trash, whereby the fire from said trash is utilized for incinerating the wet garbage and slops on said perforated plate, said supplemental stack being removably mounted in said opening in the perforated plate whereby the burned garbage and slops may be discharged through said opening in the perforated plate into said space in the bottom portion of the incinerator.

In testimony whereof I have signed my name to this specification.

SAMUEL A. DUGAN.
